UNITED STATES PATENT OFFICE.

PAUL KESTNER, OF LILLE, FRANCE, ASSIGNOR TO KESTNER EVAPORATOR COMPANY, OF PHILADELPHIA, PENNSYLVANIA, A CORPORATION OF PENNSYLVANIA.

EVAPORATING APPARATUS.

1,016,160.

Specification of Letters Patent. Patented Jan. 30, 1912.

Application filed May 10, 1911. Serial No. 826,193.

To all whom it may concern:

Be it known that I, PAUL KESTNER, a citizen of the Republic of France, and a resident of Lille, Department Nord, Republic of France, have invented certain Improvements in Evaporating Apparatus, of which the following is a specification.

One object of my invention is to provide an efficient and practical apparatus for carrying out the process described and claimed in my application for United States Patent No. 483,112, filed March 13, 1909; it being especially desired to provide a multiple effect evaporating apparatus by which it shall be possible to materially increase the extent to which the concentration of a given liquid may be safely carried, and thus reduce the quantity of water therein so as to finally deliver it in a condition substantially dry, or so nearly dry that it will solidify upon cooling.

Another object of the invention is to provide a combination of multiple effect evaporating apparatus working under successively increasing vacua, with an effect operating under a pressure above the atmosphere and at a temperature above 100° C., for the purpose of economically and safely carrying the concentration of certain liquids to considerably higher points than have hitherto been considered safe.

I further desire to provide an evaporating apparatus of the general type heretofore referred to, with means whereby the highly concentrated material shall be caused to assume a dry or practically dry form at the time of or immediately after its delivery from the last effect: the various pieces of apparatus comprising my system being so connected as to permit of the attainment of a high efficiency, both as regards cost of operation and quantity of product.

These objects and other advantageous ends I secure as hereinafter set forth, reference being had to the accompanying drawings, in which:—

Figure 1, illustrates, to some extent diagrammatically, a combination of apparatus arranged according to my invention, and Fig. 2, is a vertical section illustrating in detail a portion of the apparatus shown in Fig. 1.

In the above drawings A, B and C repre-

sent in a conventional way three multiple effect pans designed to operate under successively increasing vacua, and D represents a final effect or evaporating element for the treatment of the liquid delivered from the last of the three previously mentioned pans or elements, this final effect being preferably of the construction described and illustrated in my application 560,086, filed May 7, 1910.

A pipe 4 is connected to the pan A so as to conduct the vapor generated therein to the heating zone of the pan B and likewise a pipe 6 is arranged to conduct the vapor generated in the pan B to the heating zone of the pan C; a condenser being connected to receive the vapor from this latter pan. The juice or liquid to be concentrated is forced from a source of supply by means of a pump 2 through a pipe 1 to the pan A; this being connected by a pipe 3 so as to deliver partially concentrated liquid to the pan B, which in turn is connected through a pipe 5 so as to be capable of delivering liquid to the pan C.

Pipes 7 and 24 connect latter pan to the liquid receiving chamber d of the film evaporating element D; there being usually a pump 7^a connected in this conduit for forcing the liquid through the same and likewise a heater 9 for raising the temperature of said liquid prior to its introduction into said element.

As shown in detail in Fig. 2, the final effect or evaporating element D consists of a vertically elongated casing 20 having tube sheets 21 and 22 respectively at its top and bottom for the reception of two sets of substantially vertical tubes a and b; all of these tubes at their upper ends projecting into a chamber 23, while the tubes a at their lower ends communicate with a liquid receiving chamber d connected through a valved pipe 24 with the heater 9. The lower ends of the tubes b open into a chamber 25 for the reception of concentrated liquid, and this has a vapor outlet pipe 13 which may be connected to deliver steam into the heating chamber or zone of the first of the multiple effect pans A. This pipe may be also connected through a valve 12 with a steam supply pipe 11, so that said pan A may be heated with live steam when necessary, and said steam pipe 11 is likewise con-

ected to the casing 20 so as to supply steam for heating the tubes *a* and *b* ;—the lower portion of said casing being connected through a pipe 10 with the heater 9 so as to 5 deliver thereto the hot water and uncondensed steam which escape under operating conditions from the outlet of the heating chamber of the evaporating element D.

As shown in Fig. 1, the lower portion of 10 the chamber 25 into which is delivered the highly concentrated liquid, is connected through a pipe 26 with a casing 15, which through a pipe 16 communicates with any suitable condenser or exhausting apparatus 15 whereby a high vacuum is maintained in it. This chamber has mounted within its lower portion a receiving pan 18 to prevent the material delivered from the pipe 26 from resting directly upon the bottom of said 20 casing, and the latter is provided with a discharge pipe 19 through which may be drawn off any liquid forming therein.

In order to prevent the withdrawal 25 through the exhaust pipe of the material discharged from the pipe 26, I provide a deflector 17 around the discharge end of said pipe, which effectually prevents such an action.

Under operating conditions the liquid to 30 be concentrated is forced by the pump 2 through the pipe 1 to the first effect A and at the beginning this is heated by live steam delivered from the pipe 11. As above noted, the vapor generated in this pan passes 35 through the pipe 4 to the pan *b* to which the liquid under treatment is delivered after a certain amount of concentration, and from which it subsequently passes after a further concentration to the pan C. This latter is 40 heated by the vapor from the pan B and a successively increasing vacuum and decreasing temperatures are maintained in these various pans by means of the condenser 8, in the common and well understood manner.

45 Live steam being delivered from the pipe 11 to the heating chamber of the film evaporating element D, the partially concentrated liquid from the pan C is forced by the pump 7^a through the pipe 7 and the 50 heater 9 to the receiving chamber *d* of said element from which it passes in film form up the tubes *a* into the chamber 23. The vapor from the evaporation occurring in 55 these tubes, together with the concentrated liquid, then flows down the tubes *b* wherein it is again given a film form, as fully disclosed in my application heretofore mentioned, and is thereby evaporated to any desired extent, so that it is finally dis- 60 charged into the chamber 25 either as a syrupy liquid or in the case of sugar juices, as a molten or semi-molten sugar.

It is to be understood that in the element D the liquid under treatment is tempora-

rily exposed to relatively high temperatures 65 which may reach to 130° C., but with the particular construction of apparatus illustrated such superheated liquid readily flows through the same in filiform layers, although it is to be noted that its time of 70 transit is so short that in the case of sugar containing liquids there is little or no crystallization permitted, and in no case is there any injury to the liquid under treatment. From the evaporating element D the highly 75 concentrated liquid passes through the pipe 26 into the vacuum or expansion chamber 15, assuming on its delivery a spongy or vermicular form; while a great portion of the water still carried by the material at the 80 time of its delivery to this chamber at the same time flashes into vapor which passes off through the pipe 16.

The spongy material collecting in the pan 85 18 may be removed through a suitable opening and may be subsequently comminuted to form a light, fluffy powder capable of indefinite preservation and available for reforming the original liquid upon the addition of water. After the evaporating ele- 90 ment D has been put in operation, the supply of live steam to the pan A may be cut off by means of the valve 12 and the steam from the chamber 25 be led through the pipe 13 to said pan, as I have found that this latter 95 steam may be advantageously used for this purpose.

The hot water and steam from the heating chamber of the element D, as before noted, may be utilized in the heater 9 to 100 raise the temperature of the liquid from the low point at which it leaves the element C to such a point as will permit of its being rapidly superheated and efficiently evapo- 105 rated in the desired manner in the ele- ment D.

I claim:—

1. In an evaporating system, the combination of a plurality of evaporating elements working under increasing vacua; an evaporating element working under pressure; means connecting said elements to conduct concentrated liquid from the element of highest vacuum to the element working under pressure; and means for conducting the 110 vapor from the latter element to the heating compartments of the vacuum elements.

2. An evaporating apparatus comprising means for evaporating liquid under vacuum to a relatively dense consistency; with means for reheating and thereafter filming the dense evaporated liquid to perform a further evaporation.

3. An evaporating apparatus comprising 125 a plurality of evaporating elements connected in multiple effect; means for feeding liquid to the first of said elements; an independently heated evaporator; means for

transferring concentrated liquid from the last of the evaporating elements to said independently heated evaporator; and means for transmitting the vapor generated in 5 said evaporator to the heating compartment of said first evaporating element.

4. An evaporating apparatus comprising a plurality of evaporating elements connected in multiple effect; means for feeding 10 liquid to the first of said elements; an independently heated evaporator of the film type; means for transferring concentrated liquid from the last of the evaporating elements to said independently heated evaporator; and means for transmitting the vapor evolved in said evaporator to the heating compartment of said first evaporating element.

5. In an evaporating apparatus, a plurality of evaporators connected in multiple effect; an independently heated evaporator adapted to work under pressure; means for connecting said evaporator to receive liquid from the last of said multiple effect evaporators; a receiving chamber connected to the discharge outlet of said pressure evaporator, and means for producing a vacuum within said receiving chamber.

6. An evaporating apparatus comprising 30 a plurality of evaporating elements connected in multiple effect; an independently heated evaporator; connections for transmitting vapor from said evaporator to the heating compartments of the evaporating element; and means, including a reheater, for transmitting concentrated liquid from the last evaporating element to said evaporator.

7. An evaporating apparatus comprising 40 a plurality of evaporating elements connected in multiple effect; an independently heated evaporator of the film type; connections for transmitting vapor from said evaporator to the heating compartments of the first evaporating element; and means including a reheater for transmitting concentrated liquid from the last evaporating element to said evaporator.

8. In an evaporating apparatus a multi- 50 ple effect evaporator; means for feeding liquid to the first effect of said evaporator; an independently heated effect; means for transmitting vapor therefrom to the heating element of the first effect of the evaporator; means for conducting liquid from the last effect and introducing the same into said independently heated effect; said means including a pump and a heater; with a structure for receiving finished material 55 from said independently heated effect.

9. In an evaporating system the combination of an evaporating element for concentrating liquid under vacuum; a second evaporating element connected thereto for con-

tinuing the concentration of the liquid under 65 pressure; and an expansion chamber connected to receive the liquid delivered from said second evaporating element; with means for exhausting said chamber.

10. An evaporating system consisting of 70 an evaporating element for concentrating liquid under relatively low temperature; a second evaporating element including means for continuing the concentration of the liquid at a relatively high temperature; 75 means for connecting said two elements, including a device for raising the temperature of the liquid coming from the first element before it is delivered to the second element.

11. An evaporating system consisting of 80 an evaporating element for concentrating liquid under relatively low temperature; a second evaporating element including means for continuing the concentration of the liquid at a relatively high temperature; 85 means for connecting said two elements, including a heater for raising the temperature of the liquid from the first element before it is delivered to the second element; means for supplying steam to the second element; 90 and means for connecting the heating compartments of said second element to the heater to permit of the passage of uncondensed steam and water thereto from said heater.

12. The combination in an evaporating system of a film evaporator; a casing connected to receive liquid discharged from said evaporator; and means for exhausting said casing.

13. In an evaporating system the combination of an evaporating element including means for concentrating liquid delivered thereto; and a casing in connection with an exhausting device arranged to receive liquid 105 discharged from said evaporating element; with a receiving pan mounted within the casing but spaced away from the bottom thereof.

14. In an evaporating system the combination of an evaporating element including means for concentrating liquid at a relatively high temperature; means connected to said evaporating element for heating the liquid prior to its introduction thereto; a 110 chamber connected to receive liquid discharged from said evaporating element; an expansion chamber receiving material from said first chamber; and means for exhausting the vapor from said expansion chamber. 120

15. The combination in an evaporating system of an evaporating element including steam heating means; means for maintaining the pressure in said evaporating element below normal; a second evaporating element 125 also having steam heating means and working under a pressure above the atmosphere; means for delivering the vapor generated in

said latter evaporating element to the steam heating means of the first evaporating element; a source of live steam connected to supply the heating means of the second evaporating element; and means for connecting said source of live steam to the steam heating means of the first evaporating element.

In testimony whereof, I have signed my name to this specification, in the presence of 10 two subscribing witnesses.
